UNITED STATES PATENT OFFICE.

KANUTE ARVID ENLIND, OF WASHINGTON, DISTRICT OF COLUMBIA.

AIRSHIP.

1,365,474.

Specification of Letters Patent. Patented Jan. 11, 1921.

Application filed February 14, 1919. Serial No. 277,006.

To all whom it may concern:

Be it known that I, KANUTE ARVID ENLIND, a citizen of the United States, and a resident of Washington, in the District of Columbia, have invented certain new and useful Improvements in Airships, of which the following is a specification.

My present invention relates generally to flying machines, and more particularly to flying machines of the lighter-than-air type, known as airships, my object being the provision of an airship, the construction of which will reduce the number of essential major parts and will increase its strength, durability and general effectiveness.

More especially, my invention proposes an airship having rigid envelopes or gas tanks, certain of which are rotatable and provided with means so that upon their rotation they serve to drive the ship through the air, and my invention proposes the use of propellers having the function also of sustaining the ship in the air.

In the accompanying drawings illustrating my present invention,—

Figure 1 is a side elevation of the airship.

Fig. 2 is a vertical longitudinal section through one of the rotatable gas tanks,

Fig. 3 is a vertical cross section taken substantially on line 3—3 of Fig. 1,

Fig. 4 is a detail perspective view of a portion of one of the rotatable gas tanks,

Fig. 5 is a detail cross section taken substantially on line 5—5 of Fig. 2,

Fig. 6 is a vertical longitudinal section through the central stationary gas tank,

Fig. 7 is a detail sectional view of one of the shaft connections,

Fig. 8 is a vertical cross section taken substantially on line 8—8 of Fig. 6, and

Fig. 9 is a detail perspective view of a slightly modified form of rotating means on the gas tank.

Referring now to these figures, my invention proposes an airship in which the car or body 10 is suspended in any suitable manner as by means of either flexible or inflexible connections, or both, from a gas envelop or tank 11, which is rigid in its nature, and cylindrical in form, this tank being provided with an axially disposed tube 12 extending entirely therethrough as seen in Fig. 6, and open at its opposite ends, for

the reception of a shaft 13 rotatable within 55 the tube 12.

For the support of the car 10 in its suspended relation below the gas envelop or tank 11, this tank may be encircled by bands 14 to which the supporting wires 15 lead 60 from the said car, and for the further support of the car if so desired, uprights 16 may lead therefrom in a vertical direction and connect to arms 17 depending within the tank 11 from the central portion of its bearing tube 12, as seen best in Fig. 6.

Mounted upon brackets 18, or other suitable supports located at the opposite end of the envelop or tank 11, are motors 19 which are of course controlled from the car 10 70 through suitable connections, as, for instance, control wires 20 as seen in Fig. 1, the inner end of the shaft 21 of said motor being coupled to the opposite end of the shaft 13 by a sleeve coupling 22 as seen in 75 Fig. 7, threaded upon the ends of the shaft 13 and keyed to the ends of the two shafts 21, for instance, by means of keys 23 and pins 24.

Outwardly beyond the motors 19, the 80 shafts 21 thereof support cylindrical tanks 25 terminating in conical extremities 26 and provided with spiral vanes or ribs 27 which form air displacing screws so as to propel the ship when the motor shaft 21, and 85 consequently the tanks 25, are rotated.

As seen in Fig. 2, the conical ends 26 of the tanks 25 are preferably of separate construction, providing for their detachment in order to reach and lubricate the several 90 roller bearings 28 on the shaft 21. Each tank has an internal support in the nature of a cylindrical frame work 29 having a series of hubs 30 which support the bearings 28 and which are in turn connected to the 95 cylindrical frame 29 by a series of spokes 31.

As seen in Fig. 2 in particular, the spiral vane or fin 27 of the rotating tank 25 may be slightly and gradually increased in width from the front to the rear end of the tank. As seen in this figure and in Fig. 1, as well as in Fig. 4, the spiral vane 27 may be continuous from end to end of the tank, while as seen in Fig. 9 it may be interrupted and in the form of arcuate sections 32. In this 105 latter figure the cylindrical tank is indicated at 25^a and its conical end at 26^a.

The main stationary tank 11 has at one

end an intake normally closed by a plug 33 and an outlet similarly closed by a plug 34, and each of the two rotating tanks 25 is similarly provided with an inlet and an outlet, 5 respectively closed by plugs 35 and 36. In this way, the tanks may be readily charged when it is desired, the gas supplied thereto through its intake displacing the air and expelling the same through the outlet, which 10 is of course closed after all air has escaped.

The car or body 10, from which the motors 19 are controlled and which is supported from the tank 11 in the manner before stated, has a rudder 37 and may also have 15 any suitable and approved means of venting the tanks 11 and 25, as desired, to permit the ship to descend after flight.

The venting features last above spoken of are commonly incident to balloons and airships, and have not been illustrated in view 20 of this fact, and the further fact that the present invention resides or is confined to other and different features.

I claim:—

25 1. An airship including a car, an elongated cylindrical gas tank above and stationarily connected to the car and provided with an axial tube opening through the opposite ends thereof, a shaft journaled 30 through the tube and projecting at its opposite ends beyond the ends of the tank, and rotatable tanks forwardly and rearwardly

of the stationary tank, each mounted upon one end of the shaft and rotatable therewith and each provided with peripheral air 35 displacing means.

2. An airship including a car having rigid uprights, a cylindrical gas tank above the car having an axial tube extending therethrough provided with depending arms 40 within the tank at spaced points intermediate the ends of the tube, rigid uprights extending vertically from the car and connected through the lower portion of the tank to the lower ends of said arms, a shaft 45 having bearing through the tube, and rotatable tanks having peripheral air displacing means and mounted upon the opposite ends of the shaft as described.

3. An airship including a main stationary 50 gas tank of elongated cylindrical form, a car supported thereby, a shaft journaled axially through the said tank, tanks mounted on and rotatable with the opposite ends of the said shaft in spaced relation beyond 55 opposite ends of the main tank, motor supports carried by the opposite ends of the main tank, and motors carried by said supports in connection with the shaft between the main tank and the rotatable tanks, and 60 peripheral air displacing means carried by the rotatable tanks as described.

KANUTE ARVID ENLIND.
